H. H. CRAWFORD.
HANGER FOR USE IN CONCRETE CEILINGS.
APPLICATION FILED JUNE 30, 1919.

1,390,985.

Patented Sept. 20, 1921.

12. Inventor
Harry H. Crawford
By Arthur W. Nelson
Atty.

UNITED STATES PATENT OFFICE.

HARRY H. CRAWFORD, OF CHICAGO, ILLINOIS.

HANGER FOR USE IN CONCRETE CEILINGS.

1,390,965.

Specification of Letters Patent. Patented Sept. 20, 1921.

Application filed June 30, 1919. Serial No. 307,520.

To all whom it may concern:

Be it known that I, HARRY H. CRAWFORD, a citizen of the United States, and a resident of Chicago, Illinois, have invented a certain new and useful Improvement in Hangers for Use in Concrete Ceilings, of which the following is a specification.

My invention relates generally to hangers for the purpose of suspending line shafts, piping, or any other desired devices, from the ceiling of buildings, and relates more particularly to a hanger or fastening device adapted for use in concrete buildings. In such buildings the concrete that constitutes the floor for the story above also forms the ceiling for the story below, and after the concrete has once set it is difficult, indeed, to fix or anchor fastening devices therein.

It is an object of my invention to provide a hanger, or fastening device which can be embedded in the concrete at the time it is poured, and which shall be so effectually anchored therein that it shall be adapted to support extremely heavy loads.

Another object of my invention is to provide a device of this character which, while composed of very little metal shall be of extremely rigid and durable construction.

Again it is an object of my invention to provide a hanger or fastening device wherein portions of the metal shall be so disposed that the device shall not only be strengthened thereby, but shall also coöperate in a manner to firmly anchor the device in the concrete ceiling.

Another object of my invention is to provide a method of making a hanger, of the above character, which method shall be characterized by a plurality of steps that can be simply and easily practised with tools found in any ordinary machine shop; and in which the various parts can be quickly and easily assembled into an inseparable whole, all by the use of unskilled labor.

My invention consists generally in a hanger or supporting device, and in a method of producing the same, whereby the above named objects, together with others that will appear hereinafter, are attainable; and my invention will be more readily understood by reference to the accompanying drawings which illustrate what I consider, at the present time, to be the preferred

form of hanger and the preferred method of producing it.

In said drawings: Figure 1, is a detailed sectional view showing my hanger embedded in a concrete ceiling and showing the temporary concrete supporting structure in place. Fig. 2, is a perspective view of a piece of metal constituting part of the hanger before the same has been pressed or formed to desired shape. Fig. 3, is a side view illustrating the metal piece of Fig. 2, after it has been pressed into desired shape. Fig. 4, is a plan view of the member of Fig. 3. Fig. 5, is a plan view, and Fig. 6 is an end elevation of a piece of thin sheet metal pressed or stamped to a form adapted to coöperate with the metal member of Fig. 3. Fig. 7 is a side elevation, and Fig. 8 is a plan view similar to Figs. 3 and 4, but illustrating the cover member depicted in Figs. 5 and 6, pressed into place; and Fig. 9 is an enlarged detailed view illustrating the manner in which the cover member is held in place.

In the erection of concrete buildings or buildings having concrete floors and ceilings a temporary supporting structure is erected, usually formed of wooden planks, and the concrete is poured thereon, suitably reinforcing, having first been properly arranged. After the concrete has set sufficiently the temporary structure or support is removed.

In many buildings, particularly factory or shop buildings it is customary to hang line shafting, piping and numerous other devices from the ceiling. Where the device to be supported is a line shaft, piping or the like a large number of supporting devices must be provided throughout the length of the building, which devices must be in alignment or of such construction that the supporting portion can be readily aligned. I have devised a hanger or supporting device which can be embedded in concrete at the time it is poured, and still leave the supporting part or element that depends from the ceiling freely movable so that it can be adjusted as may be necessary to secure the desired alignment.

Inasmuch as it was necessary for me to devise a method of producing the article I shall first describe the method of production

and then add such additional description as may be necessary to describe the article of manufacture resulting therefrom.

From a strip of channel cross-section I shear a piece 1, as shown in Fig. 2 of a length suitable for the particular hanger or supporting device desired. As a next step I press or form the member 1 to the shape shown in Fig. 3, by reference to which it will be seen that it comprises a lower centrally disposed horizontal portion 2, two upper substantially horizontally disposed portions 3 and 4, and inclined connecting portions 5 and 6. In the operation of changing the channel section or piece 1 of Fig. 2, to the form shown in Fig. 3, I also form an elongated slot 7, centrally in the bottom of the channel. The slot 7 is of a width sufficient to accommodate the shank portion of a bolt 8 (see Figs. 1, 7 and 8) the head of which extends beyond the sides of the slot so that the bolt hangs therefrom. The bolt 8 may assume different forms for supporting different devices but as here indicated it is merely threaded at the end and provided with a nut 8 of usual form. Inasmuch as a number of fastening devices will be provided and inasmuch as the bolts 8 of the respective devices may not be in exact alignment it may be necessary after the hanger has been embedded in the concrete and the supporting structure removed, to shift the bolt 8 in the slot 7. This could not be done if the concrete were permitted to find its way into the bottom of the channel for obviously the head of the bolt would then be firmly embedded in concrete and all movement effectually prevented. In order to prevent any such action I provide means for effectually preventing the concrete from flowing into the bottom portion 2 of the channel. This means takes the form of a light metal stamping shown in Figs. 5 and 6, and composed of a central elevated portion or shelf 10, two base or side portions 11 and 12, and the connecting side walls 13 and 14. The distance between the side walls 13 and 14 is just sufficient so that the member can be placed over the lower central portion 2 of the channel with the inner faces of the walls 13 and 14 closely adjacent the outer side faces of the channel.

From the opposite ends of the central portion 10, of the cover member, project tongue-like portions 15 and 16 which, as is well shown in Figs. 7 and 8, extend into contacting relation to the bottom wall of the inclined portions 5 and 6, of the channel hanger, and the inclined side edges 15', 15'', 16', and 16'' of the tongues 15 and 16 are angled so that they very closely follow the inclined portions 17 and 18 of the channel side flanges.

As before stated, the portions 5 and 6 of the channel are inclined downwardly and

inwardly and it thus becomes possible to press the cover member firmly into place until it tightly engages, and in a measure embeds itself into all portions of the channel and effectually seals the same in such a manner that it becomes impossible for concrete to flow thereby.

During the same operation in which the cover is pressed into place, I prefer to perform an operation whereby the cover member shall be positively held in place against accidental separation, for it will be understood that these hangers or supporting devices are assembled with the bolt nut in place and the hanger complete as a unit before it is placed in the concrete, as before described, and that the device may receive rough handling before it is actually used. In order to so lock or bind the cover member into place I crowd some of the metal from the side flanges of the channel, preferably at four points where the cover member meets the channel, thus providing metal tongues 19, 20, 21, and 22 which, as is well shown in detailed view in Fig. 9, extend over and serve to clamp the cover tightly in place.

It will be understood that the hanger devices must be positioned properly before the concrete is poured and to this end I provide the base portions 11 and 12 of the cover members with holes 23 and 24 whereby the hanger as a whole can be fastened, as by means of brads or nails 25, to the concrete supporting structure 26 (see Fig. 1). This serves to hold the hanger in place until the concrete is poured.

The device is at once simple in construction; the channel form and its angular disposition lends great rigidity to the device and at the same time forms a larger number of pockets which assist in firmly anchoring the hanger in place; the cover member is so formed that it can be quickly and easily assembled with the channel; and all of the operations can be performed upon an ordinary punch or other light press. The steps of manufacture are relatively few in number, and readily practicable by even an unskilled workman.

In the specification or claims where I state that the bolt has its head on one side of the metal piece I wish it to be understood that if desired a nut on the bolt can be placed in that position and the head can hang therefrom. This is such an obvious reversal of parts that it is not deemed necessary to illustrate the same.

Again, while the device is much used for ceilings it may also be used in floors, side walls, and numerous other places.

Inasmuch as this disclosure will suggest to others modified methods and devices whereby the substantial objects and purposes of my invention can be attained, I do not wish to be limited to the specific device

herein shown or described, nor to the precise steps of the method or to the stated sequence thereof, except only as may be necessary by limitation in the hereunto appended claims.

I claim:

1. A hanger embodying therein a metal channel member of substantially the same cross-sectional size throughout and having its lower central portion provided with a bolt hole, continuations thereof which incline upwardly from each end of the lower central portion, a bolt having its head on one side of the channel and its shank extending through said hole, and a cover member positioned over the lower central portion, engaging the side walls of the channel and having end portions that extend into wedging engagement with said upwardly inclined continuations thereby forming a housing for said bolt.
2. A hanger embodying therein a metal channel member of substantially the same cross sectional size throughout and having a lower central portion provided with a bolt hole, portions inclined upwardly from the lower central portion, a bolt having its head on one side of the channel and its shank extending through said hole, a cover member positioned over the lower central portion, engaging the side walls of the channel and having end portions that extend into wedging engagement with said upwardly inclined portions thereby forming a housing for said bolt, and lip portions on said channel, extending over said cover member and holding it against removal.

3. A hanger embodying therein a metal channel member of substantially the same cross sectional size throughout and having a horizontally disposed lower central portion, two higher end portions and inclined portions extending therebetween, said lower central portion having a bolt hole therein, a bolt having its head on one side of the channel and its shank extending through said hole and a cover member positioned over the lower central portion, engaging the side walls of the channel, and having end portions that extend into wedging engagement with said inclined portions thereby forming a housing for said bolt.

4. A hanger embodying therein a metal channel member of substantially the same cross sectional size throughout and having a horizontally disposed lower central portion, two higher end portions and inclined portions extending therebetween, said lower central portion having a bolt hole therein, a bolt having its head on one side of the channel and its shank extending through said hole, a cover member positioned over the lower central portion, engaging the side walls of the channel, and having end portions that extend into wedging engagement with said inclined portions thereby forming a housing for said bolt, and lip portions on said channel, extending over said cover member and holding same against removal.

In testimony whereof I have hereunto set my hand, this 25th day of June, 1919.

HARRY H. CRAWFORD.
